UNITED STATES PATENT OFFICE

ROBERT F. BRACKE, OF CHICAGO, ILLINOIS, ASSIGNOR TO CURTIS B. CAMP,
TRUSTEE, OF CHICAGO, ILLINOIS

CARBURETOR FUEL SUPPLY SYSTEM

Application filed October 14, 1926. Serial No. 141,489.

My invention relates generally to carburetors and more particularly to devices of this class in which the vacuum in the induction passage is utilized to draw the liquid fuel from a low level supply tank.

It is an object of my invention to provide an improved system and means for supplying fluid fuel to a carburetor from a low level supply tank.

10 A further object of my invention is to provide an improved carburetor and float chamber in which the degree of vacuum in the float chamber is automatically regulated.

15 Other objects will appear from the following description, reference being had to the accompanying drawings, in which

Figure 1 is a central vertical sectional view of my improved carburetor and float chamber, or auxiliary tank.

20 Figure 2 is a diagrammatical sectional view of an automobile showing the relative location of the parts of my carburetor system.

Figure 3 is a central vertical sectional 25 view of a modified form of my invention.

Referring to Figure 2, it will be noticed that the supply tank 4 is connected by means of a tube 5 with the float chamber 6, and that this chamber lies at a level below that 30 of the bottom of the tank. The float chamber 6 is connected to the carburetor 7 by means of two pipes 8 and 9, as will hereinafter be more fully described. As is usual the carburetor is secured to the intake manifold by means of bolts passing through a flange 7a of the carburetor.

Referring more particularly to Figure 1, a brief general description of the carburetor will be given. An induction passage 11 is 40 formed in the carburetor body 7, the flow of the charge from this passage being regulated by a throttle valve 12. Air is admitted to this induction passage from the air inlet pipe 13, the opening of which may be controlled by the butterfly choke valve 14. When the air pressure in the induction passage 11 drops below atmospheric pressure, an air admission valve 15 which rests on a seat 16 is raised from its seat to permit the 45 passage of air from the air inlet pipe into

the induction passage. The air valve 15 is normally retained upon its seat by the compression coil spring 17 which rests in a dashpot piston 18 which is integral with the stem of the valve 15. The effective pressure of the spring 17 may be varied by rotatably adjusting the regulating nut 19 to increase or decrease the amount of compression in the spring 21 which is positioned so as to partially counteract the effect of the spring 17. 55 The dashpot arrangement prevents fluttering of the valve 15.

A Venturi tube or nozzle 22 projects within the induction passage and is screwed into the body 7 of the carburetor, an annular passage 24 being formed between the tube and the body. A plurality of ducts 25 lead from this annular passage 24 to the throat of the venturi and a tube 8 is screwed into the body so as to communicate with this 60 annular passage.

A similar tube 9 terminating in an elbow fitting 10 is screwed into the body 7 and communicates directly with the induction passage. The tube 8 extends downwardly into the float chamber 26 and terminates near its bottom while the tube 9 terminates at the top of the chamber. A fuel connection 27 is screwed into the side of the float chamber body 6 and leads into an annular chamber 28 surrounding the plug 29 which is threaded into the body. The plug 29 is axially bored at 31 and has a plurality of openings 32 communicating with the chamber 28. A screen strainer 33 surrounds the plug 29 to 70 prevent the entrance of dirt and other foreign matter into the float chamber. The fuel may pass from the bore 31 through a horizontal passage 33 which leads to a valve seat 34. A blunt needle valve 35, retained and 75 guided in the float chamber by means of a socket cap 36 threaded into the top of the body registers with the seat 34 and is adapted to control the flow of fuel from the passage 33 to the float chamber 26. Pivotally mounted on lugs 37 depending from the top of the body 6, are a pair of weighted levers 38, the outer ends of which are adapted to 80 rest on the top of the hollow metallic float 39 which is guided by the stem 35. The in-

ner ends of these levers, as is usual, fit between a pair of collars 41 formed on the stem of the needle valve 35. It will thus be apparent that the opening of the valve 35 is controlled by the position of the float. A guiding lug 42 formed integral with the bottom of the body 6 forms a centering support for the lower end of the stem of the valve 35. An air check valve comprising a seat 43 screwed in the top of the body 6 and a spring-pressed ball closure 44 prevent the formation of an excessive vacuum within the float chamber. The pressure of the ball upon its seat may be adjusted by rotation of the seat, and thus the maximum vacuum in the float chamber may be regulated.

It has been found that the vacuum in the induction passage 11 is sufficient to draw the fuel from the supply tank 4 under all ordinary circumstances even when the car is going up a steep hill. Thus the reduction of pressure in the pipe 9 is sufficient to continually maintain the required level of gasoline or other fuel in the float chamber. This is of great importance since the amount of fuel drawn through the Venturi nozzle is in part dependent upon the level of the fuel and the pressure in the float chamber. By my improved device the pressure in the float chamber is maintained at or above a predetermined minimum pressure which may be adjusted by rotation of the seat 43 of the air check valve. While, as has been said, the suction in the induction passage is sufficient to draw the fuel from the supply tank, it is not very great under normal operating conditions, so that great fluctuations of the pressure in the float chamber are improbable, thus insuring a constant pressure source of fuel supply for the carburetor.

In Figure 3 I have shown a modified construction in which the suction pipe 9' is connected to the induction passage through a duct 46 in which a perforated cylindrical cap 47 is fixed, the perforations being designated at 47'. This cap by reason of the perforations acts as a calibrating means to produce the proper suction in the float chamber. The cap 47 is positioned adjacent the head of the valve 15 and as the valve rises under the influence of induction chamber depression, the head of the same will shut off certain of the perforations 47' longitudinally spaced in the wall of the cap 47 and in registration therewith. Thus as the valve 15 rises and falls due to varying induction chamber depressions, its head will decrease or increase the number of perforations 47' exposed to induction chamber depression to vary the suction in the tube 9' to calibrate the suction effective to maintain a uniform partial vacuum in the auxiliary tank and thereby eliminating the need for an air intake valve such as shown at 44 in Figure 1. 65 In other respects the construction shown in

Figure 3 functions and operates in a manner similar to that of the construction shown in Figure 2.

The invention is capable of wide variation within equivalent limits and I contemplate such variation as may be desirable or useful in the particular adaptation of the invention shown, or in its adaptation to other similar devices. I do not restrict myself in any essential particulars, but what I claim and desire to secure by Letters Patent is:

1. In a carburetion system, the combination of a carburetor having an automatic air admission valve, a fuel suction device and an induction passage, an auxiliary tank disposed separate from and below said carburetor, a suction pipe extending into said induction passage and communicating with said auxiliary tank to create a vacuum therein, that portion of said suction pipe disposed in the induction passage being provided with a plurality of apertures in registration with the head of said valve during the course of its travel, whereby certain of the apertures are shut off from the induction passage as the valve rises, a tube connecting said carburetor suction device with the lower portion of said auxiliary tank, and means for regulating the level of fuel in said auxiliary tank.

2. In a carburetion system, the combination of a carburetor having an automatic air admission valve, a fuel suction device and an induction passage, an auxiliary tank disposed separate from and below said carburetor, a suction pipe extending into said induction passage and communicating with said auxiliary tank to create a vacuum therein, that portion of said induction pipe disposed in the induction passage being provided with a plurality of apertures in registration with the head of said valve during the course of its travel, all of the apertures being exposed to the pressure existing above the valve when the valve is closed and some of the apertures being exposed to the pressure existing below the valve when the valve rises, a tube connecting said carburetor suction device with the lower portion of said auxiliary tank, and means for regulating the level of fuel in said auxiliary tank.

In witness whereof, I hereunto subscribe my name this 9th day of October, 1926.

ROBERT F. BRACKE.
